UNITED STATES PATENT OFFICE.

JOHN S. NEHER, OF NORTH MANCHESTER, INDIANA.

SILO COVER.

Application filed October 30, 1923. Serial No. 671,792.

To all whom it may concern:

Be it known that JOHN S. NEHER, a citizen of the United States, residing at North Manchester, in the county of Wabash and State of Indiana, has invented certain new and useful Improvements in Silo Covers, of which the following is a specification.

This invention relates to an improved 10 silo cover or top and more particularly to a device of that nature than can be easily and conveniently manipulated to open or close the upper end of the silo.

The principal object of the invention is 15 to provide a silo top or cover that can be quickly and easily moved from a closed to an opened position and vice versa, and which when in an open position will be held or suspended from the top edge of the silo.

A further object of the invention is to 20 provide anti-friction means to facilitate moving the cover and improved means to guide the cover when it is moved and to maintain it in a suspended position when 25 open.

A further object of the invention is to 30 provide improved means to slightly elevate the cover as it is slid over the top of the silo, so as to prevent certain parts coming in contact with the upper edge of the silo during the opening or closing operations.

A still further object of the invention is 35 to provide an improved and simplified cover consisting of but a few simple parts that can be assembled or disassembled quickly and easily.

In the drawings:—

Fig. 1, is a vertical sectional view of my 40 invention, in its preferred embodiment and as used in connection with the silo.

Fig. 2, is a fragmentary view of a portion 45 of the upper end of a silo wall showing my cover as it is held in a suspended position when open.

Fig. 3, is a cross sectional view taken on line 3—3 of Fig. 1.

Fig. 4, is a view in bottom plan.

Fig. 5, is a perspective view of a portion 50 of the outer edge of the body of the cover.

Fig. 6, is a view in perspective of the 55 outer rim of the cover which, when in use engages and is carried by the edge of the cover as shown in Fig. 5.

The body portion 10 of the cover is practically constructed of metal and when finished assumes substantially conical form as

illustrated in Fig. 1. It is preferably formed by joining the edges of a series of substantially V-shaped sections, the edges being brought into interlocking relation to 60 form radially positioned flanges 11. The upper end of the cover is provided with an opening 12. The lower edge of the cover is engaged by a series of alternately bent ears 13 that are carried at the upper edge 65 of a circular rim 14 thereby forming a complete durable covering for a silo.

Over the opening 12 I arrange a conical closure member 15 that has cut out portions 70 16 spaced about its lower edge so that it can fit over the flanges 11. The closure member is provided with a small opening at its upper end for the purpose hereinafter described.

Within the cover I arrange suitable truss 75 members A and B. The inner truss A comprises upper and lower members 17 and 18 that are spaced apart intermediate their ends by spacing blocks 19 and which have their outer ends brought in closer relation- 80 ship through the medium of bolts 20 whereby the upper member 17 assumes a substan- tially bowed position and the lower member is slightly bowed as will be observed upon reference to Fig. 1. The truss B is formed 85 in substantially the same way as truss A, the intermediate portions of its upper and lower members passing over and under the members of truss A in alignment with the spacer blocks 19. Upon reference to Fig. 1, it 90 will be observed that the lower member 18 of the trusses is materially shorter than the upper member and that the distance between the ends of the upper members when the latter are in a bowed position is substantial- 95 ly the same as the inner diameter of the rim 14. One end of the lower member of truss B is cut slanting as 21 to cooperate with certain anti-friction means as will be hereinafter more fully described. 100

In order to maintain the trusses in binding engagement with the inside wall of the cover and thereby strengthen the cover and serve other purposes that will presently appear, a rod 22 is passed through the over- 105 lapping intermediate portion of the trusses (see Fig. 3) and extends upwardly through the opening 12 of the cover and outwardly through the opening at the top of the closure member 15. At its lower end the rod is provided with a head 23 so as to limit upward movement with respect to the trusses 110

and the upper end that projects beyond the upper end of the closure member 15 is provided with a detachable cross pin 24 to limit the downward movement of the rod with respect to the closure member. Consequently when the trusses and the rod 22 are positioned in place as shown in Fig. 1 the trusses will be firmly held within the cover and the closure member 15 will be securely seated on the cover.

The upper end of the silo as indicated by the numeral 25 is equipped with a bracket 26 as at 27, the said bracket lying inside the silo and being equipped with spaced ears 28 which carry an anti-friction member 29 through the medium of a pintle 30, it will be observed that the upper edge of the anti-friction roller 29 lies slightly above the upper edge of the silo and that it is spaced only slightly from the inner wall thereof. The anti-friction roller 29 is of substantially the same width as the lower member 18 of truss B which member is adapted to operate thereon during the opening and closing operations of the cover. It will also be noted that the upper portions of the ears 28 will form guides for the member 18 of truss B as it moves on the friction roller.

The upper edge of the silo is further provided with eye brackets 31 spaced at each side of the bracket 26 but on the outside wall of the silo for the purpose that will presently appear. The eye portions of the brackets 31 assume a position slightly above the upper edge of the silo and lie at a substantially 45 degree angle with respect to that edge.

Guide rods 32 and 33 have their inner ends secured to the upper member 17 of truss A as at 34, pass downwardly through openings in the lower member 18 of the same truss and are then bent at right angles as at 35 to extend outwardly through the eye portions of brackets 31, elongated openings 36 in the rim 14 and finally terminate in heads 37 on the outside of the rim. The rods may also be curved slightly between the point of bending 35 and their outer ends as shown in Fig. 1.

When in place, the cover assumes substantially the position shown in Fig. 1, with the bevelled edge 21 of the lower member 18 of truss B lying snugly against the anti-friction roller 29. When it is desired to open the cover the side opposite the anti-friction roller 29 is raised slightly and the cover is then pushed toward the other side of the silo. This brings lower member 18 of truss B onto the friction-roller 29 and in view of the fact that the said truss member

is slightly bowed the entire cover will be raised slightly as it slides off the silo. During this movement the guide rods 32 and 33 pass through the eye brackets 31 on the silo until the point of bending 35 is reached. The entire cover can then be tilted so as to assume a vertical position as shown in Fig. 2 and will remain suspended in such position until it is again tilted into a horizontal position and slid entirely across the silo.

From the above it will be observed that the opening and closing operation can be quickly and easily affected and that because of the anti-friction roller 29 and the slightly bowed lower member of truss B the least possible resistance is offered.

What is claimed is:

1. In combination with a silo, a top or cover portion capable of horizontal sliding movement and means to automatically elevate the same slightly during such movement substantially described.

2. In combination with a silo, a top or cover portion capable of horizontal sliding movement in one direction after one side has been slightly elevated, means to automatically elevate the top or cover as the sliding movement continues, and common means to limit the sliding movement and facilitate the tilting of the top or cover into a vertical position and to maintain the same suspended in such position.

3. In combination with a silo, a cover capable of horizontal sliding movement, and means to automatically elevate the cover during such movement and including a roller fixed to the silo and a bowed member carried by the cover and riding upon the said roller.

4. In combination with a silo, a cover capable of horizontal sliding movement, and means to automatically elevate the cover during such sliding movement, said means including a bowed member on the underside of the cover, brackets fixed to the silo and serving as guides for the bowed member, and a roller carried by the brackets and providing a bearing for the bowed member.

5. In combination with a silo, a bowed truss bridging the upper end of the silo, means hingedly connecting the truss with the silo to permit the truss to be slid horizontally, said hinge connection including means for holding the truss tilted in a fixed position at one side of the silo, and a cover carried by the said truss.

In testimony whereof I hereby affix my signature.

JOHN S. NEHER.
